UNITED STATES PATENT OFFICE.

LEE DE FOREST, OF NEW YORK, N. Y., ASSIGNOR, BY MESNE ASSIGNMENTS, TO GENERAL TALKING PICTURES CORPORATION, A CORPORATION OF DELAWARE.

DIFFRACTION MICROPHONE.

Application filed October 29, 1926. Serial No. 144,977.

This invention relates broadly to microphone construction whereby sound waves are converted into electrical current variations.

The microphone of my invention relates to 5 a device for transforming sound waves into light fluctuations, and in turn, translating said light fluctuations into electric currents.

Another object of my invention is the provision of a novel form of microphone which 10 utilizes the diffracting power of two layers of diffracting media comprising one layer of air or gas at a different temperature and pressure than a contiguous layer.

A still further object of my invention is 15 the provision of an apparatus of this type which varies the light from a constant source by and in accordance with sound waves, which light waves are impressed upon a light sensitive cell, where they are converted 20 into electrical current variations.

Another object of my invention is the provision of diffracting media adjacent to a polished reflecting surface for accomplishing 25 the above transformation.

A still further object of this invention is 30 the provision of means for heating a reflecting surface to provide adjacent diffracting media, for the purposes described above.

It is also a purpose of my invention to 35 provide a diffracting microphone utilizing diffracting media other than air, such as vapors from volatile liquids.

These and many other objects are successfully sought by the constructions disclosed 40 herein, as embodying some of the possible forms of my invention.

The invention resides substantially in the combination, construction, arrangement and relative location of parts, as will appear more fully hereinafter.

Referring to the drawings,

Fig. 1 shows a diagrammatic view of one form of my invention, using a curved reflecting surface.

Fig. 2 is a diagrammatic view showing a cylindrical reflecting surface in cross-section, utilizing the exterior of the cylinder as the reflecting surface.

Fig. 3 represents a somewhat similar form 50 in which a hollow cylinder, interrupted for part of its circumference, and polished on the inside, is used.

Fig. 4 represents another form of my invention, in which two segmental polished reflecting surfaces are shown in cross-section.

Fig. 5 represents a still further form of my invention, in which the beam of light from the light source falls upon a curved surface arranged relative to two mirror surfaces, the curved surface being very thin and flexible. 60

Fig. 6 represents a still further modified form in which provision is made for supplying a vapor from a volatile liquid to provide one of the diffracting media.

It is well known that when a polished surface is heated, the layer of air next to it becomes highly diffracting and possesses to an unusual degree the power to diffract light rays. The degree of diffraction possessed by such a layer of air depends upon the density of this layer and of the layer of air lying next thereto. This density is a function of its temperature and pressure. I have discovered that sound waves impinging upon such a succession of layers of air of 75 varying densities, can, by varying the pressure or temperature of these layers, correspondingly effect their diffracting power. I have therefore utilized this principle in constructing a microphone which utilizes a ray 80 of light from a suitable source, which, when passed through such a layer of diffracting air, becomes more or less diffracted, around the surface of the polished and heated reflecting member. The sound waves, by rapidly changing the density of this layer, will cause the light rays to penetrate with varying degree so as to influence, through a small 85 aperture, a photo-electric cell or other light sensitive device.

Referring to the drawings, the arrangement in Fig. 1 comprises a constant source of illumination 1, which may be of any suitable type, preferably electric, and a light confining member 2 by means of which the light 90 from the source 1 is confined to a relatively thin band of light. This band is transmitted through the set of lenses 3, where it is condensed so as to be projected upon the curved polished surface 4. This polished surface, as well as those to be described later, may be made of any suitable material, for example, as silver, platinum, pyrex, glass, quartz, and the like. A source of heat, such as the resistance coil 5, connected to a current source 5', may be used for heating the reflecting member 4 and the air contiguous therewith. Here again it is evident that any suitable heating means may be used in any of the constructions disclosed. The light 100 105 110

rays, after passing through the heated layer and being diffracted thereby, travel in a new direction through the atmosphere to a slit forming member 6, where the rays are again 5 confined to a thin band which is intercepted by the light sensitive device 7.

In Fig. 2, the light source 8 projects its rays on to the condensing lens system 9, which may be of any form found useful for 10 this purpose, from whence they are transmitted through the light aperture in the member 10, on to the surface of the polished cylinder 11. A number of mirrors 12, placed adjacent to the cylinders 11, but separated 15 therefrom, are arranged parallel to a tangent plane, so that the light rays after passing through the layer of heated air surrounding the cylinder 11, are diffracted or deflected so as to strike the first mirror 12. 20 They are then reflected from this mirror back to the surface of the cylinder 11, and so on until they pass through the slot in the member 13, and then finally to the light sensitive device 14, where they are 25 translated into varying electrical currents. As above, a suitable heating means 17, supplied from a power source 17', is disposed this time within the hollow cylinder 11 for heating it.

30 In the modification of Fig. 3, a light source 8', a condensing lens 9', and slit forming member 15, are provided as before. However, in this construction the cylinder 16 is hollow and polished on the interior, 35 and has its surface interrupted to permit light to enter into the cylinder, where it is reflected from the polished surface of the cylinder and diffracted by the heated air so as change its direction a plurality of times, 40 and is finally transmitted out through the opening in the cylinder and through the slit forming member 19 to the light sensitive cell or device 20. I prefer to use a thin, dark gauze screen at each end of the cylinder 16, for the purpose of shutting out extraneous light and air currents, and at the 45 same time, permitting sound waves to pass freely through the cylinder axially.

In the arrangement in Fig. 4, the light 50 rays from the source are transmitted through the heated air between two segmental polished cylinders 22 and 23, which may be specially adjusted with respect to each other by means of the thumb screws or 55 other suitable adjusting means 26. The heating coils 24 and 25 are provided for heating the polished surfaces of the segments. A slit forming member 27 again confines the light to a thin band, and the light rays are 60 transmitted to a dark chamber or supporting means 28, within which any suitable light sensitive cell may be disposed.

The arrangement of Fig. 5 is somewhat 65 different, as will appear. The rays from the light source 29 pass through the lens system

30 and the slit forming member 31, and their direction is confined by means of the mirror 33, so as to project against the curved surface 32. The member 32 may be a thin 70 surface of mica or glass, which may or may not be silvered. This surface is arranged relative to the two mirrors 33 and 34, so that the beam of light from the source is to a large degree cut off by the surfaces of 33 and 34. The remaining light is diffracted around the surface 36, passing finally through an aperture in the member 35 on to the light 75 sensitive cell 36.

In the arrangement in Fig. 6, the light ray 80 strikes against the concave surface of the member 41, which is heated by means of the heating coil 42. A vapor from any suitable volatile liquid, such as alcohol, ether and the like, is maintained adjacent to the curved polished surface of 41, and heated by contact 85 therewith. A vessel 37 is shown having the liquid 39 therein, and a stopper 38 at one end. At the other end is a porous sealing member 40, such as a sponge, by means of 90 which the liquid is gradually evaporated, and rises against the surface 41. I contemplate, 95 in my invention, when desirable, vapors of this nature or any suitable vapors may be used in connection with any of the modifications of my invention. The operation of 100 the device, except that shown in Fig. 5, is as follows:—When the air surrounding the polished surface is quiescent, the light from the source which falls on the light sensitive cell is constant. However, as soon as sound 105 waves impinge upon or are directed toward the polished heated surface, the layer of heated air will, by cooling, or by changes in density alternately diminish or increase the thickness of these layers, and thereby vary 110 the amount of light passing therethrough to the light sensitive cell by and in accordance with the sound waves effecting the diffracting power of the layer. It will, of course, be evident that this operation occurs 115 whether heated air is utilized as a diffracting medium, or other suitable vapors, such as disclosed above. In the arrangement in 120 Fig. 5, the sound waves impinge directly upon the thin curved surface, causing it to vibrate, and thus, by mechanical displacement, affecting the density of the air in contact with the surface to correspondingly vary the intensity of the light transmitted 125 therethrough to the photo-electric or other light sensitive cell. It would, of course, be evident that I could use a heating means in connection with the curved surface 32, in the arrangement of Fig. 5, if desired.

From the foregoing description, it will be 125 evident that I have devised a very new and novel form of microphone utilizing the principle of diffraction. I am, of course, aware that many changes in the details of construction and relative arrangement of parts 130

will readily suggest themselves to those skilled in the art. I do not, therefore, desire to be limited to the particular illustrative embodiments of my invention described above, but rather to the spirit and scope of the inventive thought disclosed herein and recited in my appended claims.

What I seek to secure by United States Letters Patent, is:—

- 10 1. In a device of the type described, the combination with a light sensitive means of a light source and a source of heat waves, said heated waves being adapted to influence the light from said source by and in accordance with sound waves impinging upon said source of heat waves to cause the heat waves to change their physical characteristics.
- 20 2. In a device of the type and characteristics disclosed, the combination with a light actuated device of a source of constant illumination and means for varying the quantity of illumination falling on said device by and in accordance with sound waves said means including a body of heat waves.
- 30 3. In a device of the type and characteristics disclosed, the combination with a light sensitive cell of means for producing a constant illumination, and a reflecting surface adjacent the path of said illumination, said surface having a layer of diffracting medium adjacent thereto and adapted to vary its diffracting power by and in accordance with sound waves to vary the quantity of illumination impinging on said cell.
- 40 4. In a device of the type and characteristics disclosed, the combination with a light sensitive cell of means for producing a constant illumination, and a curved polished reflecting surface adjacent the path of said illumination, said surface having a layer of diffracting medium adjacent thereto and adapted to vary its diffracting power by and in accordance with sound waves to vary the quantity of illumination impinging on said cell.

fracting medium adjacent thereto and adapted to vary its diffracting power by and in accordance with sound waves to vary the quantity of illumination impinging on said cell. 45

5. In a diffraction microphone, the combination of a light source with a polished surface, means for heating said surface to envelope it in a layer of heated air and a light sensitive cell adapted to receive light from said source varied by and in accordance with sound waves transmitted through the layer of heated air. 50

6. In a diffraction microphone the combination with a light source of a hollow reflecting body, means within for heating the surrounding gas, and a light actuated device, the light falling on said device being varied by and in accordance with sound waves striking said heated gas. 55

7. In a diffraction microphone, the combination with a light source of a hollow reflecting body having a light aperture and a polished interior surface, heating means within said body and a light actuated device arranged to receive the light from said source after passing into and out of said aperture. 65

8. In a diffraction microphone, the combination with a light source of a hollow reflecting body having a light aperture and a polished interior surface, electrical heating means within said body and a light actuated device arranged to receive the light from said source after passing into and out of said aperture. 70

In testimony whereof I have hereunto set my hand on this 25th day of October, A. D. 1926.

LEE DE FOREST.
